UNITED STATES PATENT OFFICE.

ROBERT ALEXANDER MOORE, OF NEW YORK, N. Y.

AUTOMATIC FIREARM.

1,376,456.

Specification of Letters Patent.

Patented May 3, 1921.

Application filed February 4, 1920. Serial No. 356,354.

To all whom it may concern:

Be it known that I, ROBERT A. MOORE, a citizen of the United States, residing at New York, in the county of New York and State 5 of New York, have invented certain new and useful Improvements in Automatic Firearms, of which the following is a specification.

The present invention relates to certain 10 new and useful improvements in the construction of recoil or gas operated automatic firearms, and has for its object to provide a device of this character which embodies novel features of construction whereby the 15 sliding movement of the barrel produced by the discharge of the cartridge will automatically reload and recock the weapon so that it can be again fired by releasing the safety and pulling the trigger.

20 Further objects of the invention are to provide a gas operated firearm of this character which embodies few and simple parts, which can be readily assembled or taken apart, which is dependable in its operation, 25 and can be fired rapidly without danger of jamming, and which provides a safe and effective weapon.

Other advantages and valuable features 30 will appear as the description proceeds, and while I am describing and illustrating one particular embodiment of the invention, it will be understood that many changes and alterations are possible in the details of construction without departing from the spirit 35 of the invention as set forth in the claims.

In the drawings, which illustrate a preferred embodiment of the invention—

Figure 1 is a sectional elevation of an automatic pistol which is constructed in accordance with the invention, the trigger being shown in the position assumed when it is pulled rearwardly and the hammer being shown as lowered.

Fig. 2 is a side elevation of the pistol.

45 Fig. 3 is a transverse sectional view on the line 3—3 of Fig. 1.

Fig. 4 is an end view of the barrel.

Corresponding and like parts are referred to in the following description and indicated 50 in all the views of the drawings by the same reference characters.

Referring to the drawings, which illustrate one possible embodiment of the invention, the numeral 1 designates a handle 55 which has a hollow formation and houses a magazine 2 within which the cartridges 3

are held preparatory to being fired. The usual trigger guard 4 is provided in connection with the handle, and a slideway 5 is arranged above the trigger guard.

60

A sliding barrel 6 is mounted upon the slideway 5 and the breech end of the barrel is normally forced rearwardly against the breech block 7 by the action of a coil spring 8. The lower side of the barrel is formed 65 with a longitudinally extending rib 9 which is slidable within the slideway 5, said rib being formed with outstanding flanges 9^a which operate within corresponding undercut portions at the sides of the channel 10 70 of the slideway. The barrel is thus free to slide forwardly against the action of the spring 8, although it is locked against lateral displacement, and is normally held in a yielding engagement with the breech block 75 10 by the action of the spring. This breech block is fixed, being shown as integral with the upper end of the handle.

The coil spring 8 is interposed between 80 a lug 11 which projects downwardly from the rear end of the barrel and a removable stop or abutment 12 which is fitted in the forward end of the slideway 5. This removable stop member 12 is normally held in 85 position by a detent 13 which is pivoted at 14 on the trigger guard, and the forward end of the coil spring 8 is loosely received upon a positioning pin 15 projecting from the stop. With this construction it will be obvious that by first releasing the detent 13 90 and taking out the stop 12 the sliding barrel and coil spring can be removed from the handle.

The hammer 16 is pivotally mounted at 17 in a recess 18 at the back of the handle 1. 95 Any conventional form of main spring may be provided for actuating the hammer, and the hammer is provided with a pin 19 which loosely engages a hammer controlling arm 20 projecting rearwardly from a trigger 100 lever 21. This arm 20 is offset laterally from the trigger lever 21, as indicated very clearly by Fig. 3, so that it can extend rearwardly through the handle at one side of the magazine 2 and will not interfere with 105 the movement of the cartridges 3 through the magazine. The pivot end of the hammer is provided with a pair of notches 22 which are adapted to be engaged by a safety member 23 for the purpose of locking the hammer either at half-cock or full-cock positions. A spring 24 normally holds the 110

safety member in operative position, and a wing or finger-piece 25 extends rearwardly from the safety member through an opening in the back of the handle so that it can be readily forced inwardly to release the safety by pressure thereon with the hand when it is desired to discharge the firearm.

The trigger lever 21 extends downwardly from its pivot pin 34 and is provided at its lower end with a notch 27 which is adapted to be engaged by a dog 28 to hold the hammer in full-cock position. A spring 29 normally tends to urge the dog into operative position, and said dog is provided with a notch 30 adapted to be engaged by a pawl 31 which is carried by the trigger 32. A spring 33 normally tends to force the pawl 31 into operative position. The trigger is pivoted at 26 and a spring normally holds the trigger in inoperative position. When the hammer is cocked the trigger lever 21 is swung rearwardly so that the dog 28 engages the notch 27 at the lower end thereof. The pawl 31 of the trigger also engages the notch 30 of the dog. An operative connection is thereby produced between the trigger and the hammer so that, assuming the safety member to be released, a pull upon the trigger will release the hammer and permit it to strike against the firing pin 36. This will discharge the cartridge which is in position within the chamber of the barrel, and the action of the gas or recoil will cause the barrel to move forwardly against the spring 8. Upon the forward movement of the barrel the head of the spent cartridge will be engaged by some conventional form of extractor so that the shell will be thrown laterally or upwardly and discharged from the firearm before the return of the barrel to its original position.

Upon the forward movement of the barrel the lug 11 thereof rides upon cocking arm 37 which is integral with the trigger lever 21 and extends forwardly therefrom. This cocking arm is thereby swung downwardly, and the hammer controlling arm 20 moved to return the hammer to a full-cock position. The safety member 23 then engages one of the notches 22 of the hammer, while the dog 28 and pawl 31 automatically swing into operative position.

The magazine 2 extends upwardly through the handle in an angular relation to the barrel, and the cartridges in the magazine rest upon each other in a superposed relation. A magazine follower 38 normally tends to urge the cartridges upwardly, and a spring 39 is interposed between the follower and a slide 40 which closes the lower end of the magazine. The uppermost cartridge in the magazine is held yieldably against a recessed portion 41 in the bottom of the breech end of the barrel, and when the barrel moves forwardly the spent shell is discharged by the

ejector and the uppermost cartridge of the magazine moved upwardly into position between the breech-block and the barrel so that it will enter the chamber of the barrel when the latter is returned to normal position by the spring 8. The heads of the cartridges in the magazine have a stepped relation to each other, and a stop arm 42 is arranged at one side of the breech-block in such a manner as to engage the cartridge immediately below the uppermost cartridge of the magazine and thereby prevent more than one cartridge from being moved upwardly into position to enter the chamber of the barrel when the barrel is moved forwardly by the discharge of the firearm. Upon the return of the barrel to its original position the stop member 42 is engaged thereby and swung rearwardly so that the then uppermost cartridge of the magazine can move upwardly into a yielding engagement with the recessed portion 41 of the barrel.

It will thus be obvious that with the magazine full of cartridges, the parts being in the position shown in Fig. 1, it is merely necessary to cock the hammer and move the safety member into inoperative position in order to discharge the firearm by pulling upon the trigger. The discharge of the firearm will operate automatically to slide the barrel forwardly, whereupon the hammer is again moved to a full-cock position and the uppermost cartridge of the magazine elevated into position to enter the chamber upon the return of the barrel. The cartridges of the magazine can thus be fired with great rapidity, and the magazine is all so simple that there is nothing to break or get out of repair. A sliding lock 43 is shown as provided at one side of the pistol, and this lock can be urged upwardly into engagement with a corresponding recess in the barrel for the purpose of locking the barrel in a forward position when it is desired to clean the barrel or inspect the bore thereof. This also enables access to be obtained to the magazine if it is desired to load the pistol from the top thereof.

Having thus described the invention, what I claim as new and desire to secure by Letters Patent, is:

1. In a fire arm having a sliding barrel, a hammer, a trigger, and an integral three armed lever, one of the arms being operatively connected with the hammer, while another arm has an operative connection with the trigger and the third arm is acted upon by the sliding of the barrel to cock the hammer.
2. In a fire arm having a sliding barrel, a hammer, a trigger, an integral three armed lever, one of the arms of which is operatively connected to the hammer while another arm has an operative connection with the trigger and the third arm is ar-

ranged at an angle to the barrel, and means upon the barrel for engaging the said third arm to swing the lever and cock the hammer.

3. In a firearm having a sliding barrel, 5 a hammer, a trigger, said barrel being provided with a lug, a spring engaging the lug to return the barrel to normal position, a trigger arm operatively connected to the hammer and trigger, and a cocking arm associated with the trigger arm and arranged 10 in the path of the before mentioned lug for actuation thereby to cock the hammer on the movement of the barrel.

4. In a firearm having a sliding barrel, a 15 hammer, a trigger, a trigger lever associated with the trigger to hold and release the hammer, a rearwardly extending arm carried by the trigger lever and engaging the hammer, and a forwardly extending arm carried 20 by the trigger lever and arranged to be moved by the sliding of the barrel to cock the hammer.

5. In a firearm having a sliding barrel, a 25 hammer, a trigger, a trigger lever associated with the trigger, a hammer controlling arm rigid with the trigger lever and extending rearwardly into operative engagement with the hammer, a cocking arm integral with the trigger lever and extending forwardly therefrom, a lug on the sliding barrel for engagement 30 with the cocking arm to swing the same and cock the hammer on the forward movement of the barrel, and a spring engaging the lug for holding the barrel normally in operative position.

6. In a firearm having a sliding barrel, a 35 hammer, a trigger, a pivotally mounted trigger lever operatively connected to the hammer, a dog arranged for engagement with the trigger lever to hold the hammer in a cocked position, and means on the trigger for disengaging the dog from the trigger lever.

7. In a firearm having a sliding barrel, a 45 hammer, a trigger, a pivotally mounted trigger lever operatively connected to the hammer, a dog arranged to engage the trigger lever to hold the hammer in cocked position, and a pawl carried by the trigger for engagement with the dog to release the 50 same.

8. In a firearm having a sliding barrel, a

hammer, a trigger lever, an integral arm extending rearwardly from the trigger lever and operatively connected to 55 the hammer, an integral cocking arm extending forwardly from the lever, means on the barrel for engaging the cocking arm to cock the hammer upon the forward movement of the barrel, a dog for engagement 60 with the trigger lever to hold the hammer in a cocked position, and means carried by the trigger for engaging the dog to release the same.

9. In a firearm having a sliding barrel, a 65 hammer, a trigger, a trigger arm operatively connected to the hammer so as to be movable therewith, trigger controlled detents engaging the trigger arm, a cocking arm rigid with the trigger arm, and means upon the 70 barrel for engaging the cocking arm to actuate the same and thereby cock the hammer on the movement of the barrel.

10. In a firearm having a sliding barrel and a slideway upon which the barrel is mounted, 75 a removable stop for the forward end of the slideway, means for locking the removable stop in position, a lug projecting from the barrel, and a spring interposed between the lug and the stop for normally holding the barrel yieldably in operative position.

11. In a firearm having a sliding barrel, a 85 slideway upon which the barrel is mounted, a hammer, a stop at one end of the slideway, a lug projecting from the barrel, a spring interposed between the lug and the stop to hold the barrel normally in operative position, an inclined arm arranged in the path of the lug, and means actuated by the 90 swinging of the inclined arm by the action of the lug thereon to cock the hammer.

12. In a firearm having a sliding barrel, a 95 hammer, a trigger, a pivotally mounted trigger arm operatively connected to the hammer so as to be movable therewith, trigger controlled detents engaging the trigger arm, a cocking arm rigid with the trigger arm, and means upon the barrel arranged to have a cam action upon the cocking arm to swing 100 the trigger arm and thereby cock the hammer on the forward movement of the barrel.

In testimony whereof I affix my signature.
ROBERT ALEXANDER MOORE.
